UNITED STATES PATENT OFFICE.

WALTER PHILIP BRAENDER, OF PASSAIC, NEW JERSEY.

DESIGN FOR AN AUTOMOBILE-TIRE.

48,854.

Specification for Design.

Patented Apr. 11, 1916.

Application filed September 11, 1914. Serial No. 861,294. Term of patent 14 years.

To all whom it may concern:

Be it known that I, WALTER PHILIP BRAENDER, a citizen of the United States, residing at Passaic, in the county of Passaic and State of New Jersey, have invented a new, original, and ornamental Design for an Automobile-Tire, of which the following is a specification, reference being had to the accompanying drawing, forming part thereof, wherein the figure illustrates an

automobile tire having tread surface ornamentation in accordance with the invention.

I claim:

The ornamental design for automobile tire, as shown.

WALTER PHILIP BRAENDER.
